UNITED STATES PATENT OFFICE.

CHRISTOPHER H. SHOEBRIDGE, OF NEW YORK, N. Y.

FUSIBLE SERVICE-PROTECTOR.

1,256,066.

Specification of Letters Patent. Patented Feb. 12, 1918.

Application filed December 18, 1916. Serial No. 137,512.

To all whom it may concern:

Be it known that I, CHRISTOPHER H. SHOE-
BRIDGE, a citizen of the United States, and
resident of New York city, borough of Man-
hattan, in the county of New York and State
of New York, have invented certain new
and useful Improvements in Fusible Service-
Protectors, of which the following is a speci-
fication.

- 10 In certain electric circuits, such as on
flexible extensions from service lines, when
a short circuit occurs in such extension line,
the service line is liable to be blown or a
fuse in such line will be blown, placing all
15 the lights or other apparatus on the line out
of use until repairs are made. The object
of my invention is to provide means in the
extension line to include a fuse therein, be-
tween the lamp or other instrument on such
20 line and the socket or outlet to which the
latter is connected, whereby if such exten-
sion line becomes short circuited, such fuse
will be blown and thereby will protect the
service line, whereby it will be necessary to
25 substitute another extension line for the
short-circuited one and the use of the system
can proceed, thereby avoiding blowing out
or injuring such circuit or any apparatus
thereon.
- 30 In the form of my invention illustrated in
the accompanying drawings I provide an in-
sulating member having a threaded sleeve
in an ordinary manner to screw into a socket
or outlet on the service line, said member
35 having an extension wire or conductor in-
sulated therein and connected with said
sleeve, the member also having a terminal
within the sleeve with a wire insulated in
the insulating member connected with said
40 terminal, said wire leading to a sleeve buried
in said member, said sleeve being adapted
to receive an ordinary fuse plug to make
circuit between its sleeve and the sleeve of
said member through the fuse in the plug.
- 45 to the central terminal of the latter and
buried in the insulating member is a termi-
nal connected to a wire or conductor of such
extension line having its end portion buried
in said member, said terminal being adapted
50 to be engaged by the central terminal of the
plug when the latter is screwed into the
last named sleeve of said member, whereby
the fuse plug is included in series in the ex-
tension line. The arrangement is such that
55 if a short circuit occurs on said extension
line the fuse of said plug will be blown,

thereby protecting the service line, and
whereby such member and its extension line
may be removed and another replaced and
said removed extension line may be repaired 60
for further use.

Reference is to be had to the accompany-
ing drawings forming part hereof, wherein,

Figure 1 is a side view illustrating my im-
provements in position on an outlet; 65

Fig. 2 is a plan view of my improved
fusible service protector on an enlarged
scale, and

Fig. 3 is a section on the line 3, 3, in
Fig. 1. 70

In the accompanying drawings the nu-
meral 1 indicates an insulating member which
may be made of hard rubber, porcelain or
other suitable material, and the same is
shown provided with a branch 2 having an 75
exterior metallic sleeve 3 thereon, and with
a branch 4 to contain a fuse plug. At 5 is
a conductor of the extension line 6 which is
shown buried in the insulation of member 1
and connected with sleeve 3, as at 7, in an 80
ordinary manner, as by solder. At 8 is a
central terminal in the branch 2, comple-
mental to sleeve 3, and connected with a con-
ductor 9, as by solder, as at 10, in a well-
known manner, said conductor being buried 85
in the insulating material of member 1, the
opposite end of such conductor being con-
nected to a metal sleeve 11 that is located in
a recess 12 in branch 4 of member 1. At 13
is indicated generally a fuse plug, having the 90
insulating block 14 carrying the metal
sleeve 15 to screw into sleeve 11, and having
the fusible metal 16 secured to sleeve 11, as
by solder, in an ordinary manner, and con-
nected with the central terminal 17 of the 95
plug. The terminal 17 is adapted, when the
plug is screwed into sleeve 11, to engage a
terminal 18 part of which is buried in the
insulating material of member 1 in axial
alinement with recess 12, thereby being com- 100
plemental to the internal sleeve 11, the ter-
minal 18 being connected with conductor 19
of the extension line, as at 20, by means of
solder or in any suitable manner. The inner
portion of conductor 19 is buried in the in- 105
sulating member 1. It will be observed that
the fuse plug is in series in the extension
line.

Any suitable electrical instrument, such
as a lamp 21, may be connected with the ex- 110
tension line in any well known manner.

In using my improvements it is merely

necessary to screw the sleeve 3 into the socket or outlet 22 of an electrical service line in an ordinary manner of connecting an extension line to the service line, and 5 thereupon the fuse plug 18 will be in series in said line, so that if such extension line should become short-circuited the fusible metal 16 of the fuse plug will be blown, thereby protecting the service line from being 10 blown or other damage. It will then merely be necessary to remove the member 1 of such short circuited extension line from the socket 22, and attach another extension line equipped with my improvements to such 15 socket, whereby the use of an extension on said service line may be continued. After a short circuited extension line equipped with my improvements has been removed from socket 22 it may be repaired and resupplied 20 with a fuse plug ready for use again. My improvements will be found of advantage in many relations, particularly in underground tunnel work, foundations, excavations and the like where extension lines are 25 most liable to be injured owing to the character of work being carried out, since merely an extension line will be temporarily put out of commission instead of the whole service line to which such extension has been 30 connected, which extension line will have prevented blowing of the service line.

My improvements may be used in extension lines embodying any desired electric appliances, such, for instance, as lamps, sad- 35 irons, toasters, dental engines, vibrators, motors, fans, and the like.

Having now described my invention what I claim is:—

1. A service protector comprising a member having an external and an internal 40 threaded sleeve, a terminal adjacent to the external sleeve and electrically connected with the other sleeve, a terminal for a plug complementary to the last named sleeve, extension lines operatively connected with the last named terminal and with the first named sleeve, and a fuse plug adapted for connection with said internal sleeve and its complementary terminal.
2. A service protector comprising an insulating member having a branch provided with a threaded sleeve and having a recess provided with a threaded sleeve, a terminal secured in said branch with relation to the 45 external sleeve, a terminal communicating with said recess and secured in said member in complementary relation to the internal sleeve, extension conductors having portions buried in said insulating member, one of

which conductors is connected to the external sleeve and the other connected to said complementary terminal, and a fuse plug adapted to screw into the internal sleeve and to coact with its complementary terminal for inclusion in series in said extension conductors.

3. A service protector comprising an insulating member having a branch provided with an external sleeve, a terminal partially buried in said branch, said member having a recess, a threaded sleeve within said recess, a conductor buried in said insulating member and connected with said terminal and with said internal sleeve respectively, a terminal having a portion buried in said member and complementary to said internal sleeve, extension conductors having portions buried in said insulation, one of said conductors connected to said external sleeve and the other conductor connected to said complementary terminal, and a fuse plug adapted to screw into said internal sleeve and to connect with said complementary terminal to include said plug in series with said extension conductors.

4. A service protector comprising an insulating member, extension conductors having portions extending into said member, said member having a sleeve connected with one of said conductors and a terminal for a fuse plug connected with the other of said conductors, said member having a sleeve complementary to the last named terminal, a plug adapted to screw into said sleeve and to coact with said terminal, said member having a terminal complementary to the first named sleeve and electrically connected with the second named sleeve whereby the plug is included in series in said extension conductors.

5. A service protector comprising a member having associate terminals to coöperate with complementary terminals of an outlet of a service line, extension conductors connected with said member and one of said conductors connected to one of said first named terminals, a terminal in said member connected to the other of said extension conductors, said member having a recess communicating with said last named terminal, a sleeve in said recess connected to the other of said first named terminals, and a plug adapted to screw into said sleeve to connect its fuse in series with the internal sleeve and said terminal in said member.

Signed at New York city, in the county 115 of New York and State of New York this 4th day of December A. D. 1916.

CHRISTOPHER H. SHOEBRIDGE.
